E. FREUNDLICH

REFRIGERATING MACHINE

Filed May 5, 1921

INVENTOR:

Erich Freundlich

UNITED STATES PATENT OFFICE.

ERICH FREUNDLICH, OF DUSSELDORF, GERMANY.

REFRIGERATING MACHINE.

Application filed May 5, 1921. Serial No. 467,223.

To all whom it may concern:

Be it known that I, ERICH FREUNDLICH, a citizen of the German Empire, residing at Dusseldorf, Germany, have invented certain new and useful Improvements in Refrigerating Machines, for which I filed an application in Germany Feb. 14, 1920, and of which the following is a specification.

My invention relates to refrigerating machines, more especially of the type operated with overheating, and its particular object is to so combine the compressor and the liquid feed pump that this latter be driven directly by the compressor.

Up till now the number of rotations of the compressors generally employed rendered it impossible to let the compressor drive the liquid feed pump directly, such as by making an extension of the piston rod of the compressor act as feed piston for the said pump, for in doing so the liquid would have been accelerated too much. It has merely been proposed to actuate the piston of the pump against the action of a spring by means of the steam pressure prevailing in the compressor.

I succeed in utilizing an extension of the piston rod of the compressor as the piston of the liquid feed pump, without altering the working speed and dimensions of the compressor piston, by disposing the suction port or ports of the pump near the end of the stroke or near the cover in such wise that the pump will feed liquid only at the lowered speed attained by the piston near the end of its stroke.

Preferably the suction ports of the liquid pump narrow down in the direction towards the pressure valve mounted in the cover in such manner that shortly before the pressure valve opens, the pressure is gradually increased so as to ensure a more gentle opening of the valve.

In the drawings affixed to this specification and forming part thereof a combined compressor and pump embodying my invention are illustrated diagrammatically by way of example.

In the drawings—

The figure is a vertical section of my device.

Referring to the drawings, *a* is the piston rod of the compressor and *s* is an extension thereof projecting through the cylinder cover and serving as piston of the liquid feed pump. *c d* is the suction chamber of

the pump, said chamber communicating with the pump chamber by way of one or a plurality of suction ports *b* and a channel *g*. In the pump cover there is mounted the spring actuated pressure valve *i* and the pressure chamber *k*. The suction chamber *c, d* receives the liquid through pipe *f*, while pipe *l* serves to carry the liquid escaping from the pressure chamber *k*. As shown in the drawing, the suction ports *b* are reduced in width towards the pressure valve in a wedge like manner.

This device operates as follows: On the piston *s* of the pump moving in the direction of the compressor the suction ports *b* are uncovered and liquid is sucked into the chamber *c, d* through pipe *f*, the pump chamber *e* being thus filled with liquid. As the piston *s* returns, first of all the liquid in excess will flow through the suction ports *b* back into the chamber *c, d*, while such gases as may be present, will escape through channel *g* into part *d* of the chamber which acts as an air chamber. As the end of piston *s* moves past the suction ports *b*, owing to the reduced area of these ports a gradual increase of pressure arises which results in the pressure valve *i* opening gently.

After the valve has opened the liquid flows into the pressure chamber *k* which forms an air chamber and is carried through pipe *l* back into the injection or pressure piping of the plant.

I wish it to be understood that I do not desire to be limited to the exact details of construction shown and described, for obvious modifications will occur to a person skilled in the art.

I claim:

1. In a refrigerating machine in combination, a compressor, a piston and piston rod in said compressor, a liquid feed pump connected with said compressor, an extension of said piston rod projecting into said pump and forming the piston therein, a suction port in said pump disposed near the end of the pressure stroke of said pump piston corresponding to the minimum velocity thereof and a pressure valve closing said pump, the section of said port being reduced in the direction towards said valve.

2. In a refrigerating machine the combination with a compressor chamber, and a piston adapted to move in said chamber of a liquid feeding pump connected to said compressor in axial alignment therewith,

a piston chamber in said pump, and of smaller diameter than the compressor, a piston in said pump chamber connected to said compressor piston in axial alignment therewith, a suction chamber near the end of the pressure stroke of said pump piston, a pressure chamber beyond the end of said pump piston chamber, and communicating therewith, suction ports between the suction 5 chamber and the pump piston chamber and of endwise decreasing area, and a controlling valve intermediate said ports and said pressure chamber, and liquid induction and eduction conduits respectively connected 10 to said suction and pressure chambers.

3. In a refrigerating machine the combination with a compressor, and a piston movable in said compressor, of a liquid feed

pump connected to said compressor, a piston chamber in said pump and of smaller 20 diameter than said compressor, a pump piston connected in axial alignment with said compressor piston, a pressure chamber at the free end of said piston chamber, and a suction chamber near the end of the pressure stroke of said pump piston, throttlingly operating communicating passages between 25 said suction and pump piston chambers, an axially displaceable pressure valve intermediate said passages and said pressure chamber and induction and eduction conduits respectively connected to said suction and said pressure chambers.

In testimony whereof I affix my signature.

ERICH FREUNDLICH.
